COSMETIC DISPLAY SELF-SERVICE COUNTER

Douglas J. Alippe, Tuxedo, and Frank A. De Sisto,
Yonkers, N.Y., assignors to J. C. Penney Company,
Inc., New York, N.Y.

Filed Sept. 24, 1970, Ser. No. 25,564

Term of patent 14 years

Int. Cl. D6—04

U.S. Cl. D6—146

FIG. 1

FIG. 2

FIG. 3

FIG. 4

FIG. 5

FIG. 6

FIG. 7

FIG.8

FIG.9

FIG. 10

FIG.11

FIG.12

FIG. 1 is a perspective view of a cosmetic display self-service counter showing our new design;

FIG. 2 is a top plan view thereof;

FIG. 3 is a front elevation view thereof;

FIG. 4 is a perspective view of a modified form of the cosmetic display self-service counter shown in FIG. 1;

FIG. 5 is a top plan view of the modified base cabinet unit;

FIG. 6 is a front elevational view of the modified base cabinet unit;

FIG. 7 is a perspective view of a second modified form of the cosmetic display self-service counter shown in FIG. 1;

FIG. 8 is a top plan view of the modified base cabinet unit;

FIG. 9 is a front elevational view of the modified base cabinet unit;

FIG. 10 is a perspective view of a third modified form of the cosmetic display self-service counter shown in FIG. 1;

FIG. 11 is a top plan view of the modified cabinet and wall unit; and

FIG. 12 is a front elevational view of the modified cabinet and wall unit.

We claim:

The ornamental design for a cosmetic display self-service counter, substantially as shown and described.
